UNITED STATES PATENT OFFICE

141,292

DESIGN FOR AN AIRPLANE

Harland M. Poyer, Lewiston, N. Y., assignor to
Bell Aircraft Corporation, Buffalo, N. Y.

Application August 10, 1944, Serial No. 114,808

Term of patent 14 years

(Cl. D71—1)

To all whom it may concern:

Be it known that I, Harland M. Poyer, a citizen of the United States, residing at Lewiston, in the county of Niagara and State of New York, have invented a new, original, and ornamental Design for Airplane, of which the following is a specification, reference being had to the accompanying drawings, forming part thereof.

Figure 1 is a top plan view of an airplane showing my novel design.

Figure 2 is a front end elevational view of the airplane shown in Figure 1; and

Figure 3 is a side elevational view of the airplane of Figures 1—2.

I claim:

The ornamental design for an airplane, as shown.

HARLAND M. POYER.
